ton, Mass., a partnershipNo Drawing. Application July 28, 1948,
Serial No. 41,172

12 Claims. (Cl. 204—77)

1 This invention relates to the production of sorbitol or other polyhydric alcohols by the electrolytic reduction of glucose or other sugars in buffered acid solution.

It has been appreciated for many years that the electrolytic production of sorbitol from glucose may be carried out in aqueous acid solution with considerable advantage in respect to yield and quality over employment of an alkaline solution. Information as to the status of the prior art will be found in the Creighton Patent 1,990,582 and Hales Patent 2,300,218 of the Atlas Powder Company. There are, however, serious difficulties in the way of controlling the pH of acid electrolytes. For example, slight changes in concentration of the electrolytes will result in large pH changes, which in turn make very difficult the maintenance of good reduction conditions. Furthermore, low temperatures must be rigidly maintained if high quality material is to be produced.

I have discovered a simple, inexpensive and reliable process of producing sorbitol and other polyhydric alcohols by electrolytic reduction of glucose and other sugars in acid solution which solves the problem of control and leads, among other things, to the complementary advantage of the employment of much higher temperature levels in operation. My novel process is characterized by the employment of an acid cathodic solution of an anionic buffer salt and the sugar to be reduced. The bulk catholyte pH may be maintained at any point between 7.0 and 2.5; the anolyte pH is normally very low.

My process is also characterized by the employment of a permeable diaphragm separating anode and cathode compartments, of such porosity and permeability that the current density employed can be used to set up a voltage gradient through the diaphragm sufficient to induce the phenomenon of electroendosmosis. Electroendosmosis is the bulk movement of liquid from one electrode to the other through the diaphragm under the influence of the electric current. Bulk movement may be controlled by varying the current density. I can, therefore, use electroendosmosis as an exceptionally effective and precise method of controlling pH. Since I also employ an acid catholyte buffered by the alkali salt of a weak acid, I am able to run the process without attention once the proper conditions are established and without substantial change in the pH of the catholyte or departure from ideal conditions.

Going more into detail, I employ as the buffer

2 in my process an alkali salt of a weak acid, for example, sodium acid phosphate or sodium acid carbonate. The phrase "phosphate anion" is used herein to include any or all of the group of anions consisting of $H_2PO_4^-$, HPO_4^{2-} , PO_4^{3-} , or PO_3^{2-} and its polymers, e. g. $P_2O_7^{4-}$; while "carbonate anion" is used to include any or both of the anions of the group consisting of HCO_3^- , and CO_3^{2-} .

10 My process is further characterized by the positive steps which are taken to insure the formation and maintenance of a thin alkali film at the cathode surface. The sugar on passing through the alkali film to the cathode surface is converted to the enolic form in which form it may be reduced to the corresponding polyhydric alcohol by hydrogen liberated at the cathode surface. The major body of the catholyte remains acid and the sugar in non-enolic form. **15** By this procedure of establishing an alkali film at the cathode surface while the bulk catholyte remains in buffered acid solution at any desired pH between 7.0 and 2.5, I develop conditions under which the sugar itself will act as an effective depolarizing agent. The establishment of the thin alkali film in the presence of a bulk buffered acid catholyte may be effected by applying a liquid alkali, such as sodium hydroxide, to the cathode surface or by the electroendosmosis of bulk acidic anolyte to acidify an originally alkaline buffer catholyte or by other expedients which will be pointed out hereinafter.

An important advantage of the process of my invention is that it permits continued operation **20** at a high temperature level without upsetting the reducing conditions and without adversely affecting normal high quality of the product. Where sodium sulphate has been employed as the electrolyte, it has been found necessary to remove heat from the cell by refrigeration in order to maintain the control for high quality production. For instance, a catholyte temperature of close to 20° C. is needed with sodium sulphate electrolyte if a high quality product is to be produced. In my process, on the contrary, temperature levels of 40°-50° C., may be utilized with good results. Furthermore, pH control of a solution containing sodium sulfate has been generally found to be an extremely delicate matter requiring constant attention. By employing a catholyte buffered with the alkali salt of a weak acid and by making use of the phenomenon of electroendosmosis, I am able to run the process without attention and without substantial change in the pH of the catholyte. I believe that

this is due to the fact that sodium sulfate (the only electrolyte salt found usable in acid solution in prior processes) is the salt of a strong acid and a strong base and hence offers no buffering action comparable to that of anionic buffers, such as the sodium phosphates or carbonates, which are salts of weak acids. This may mean that when using sodium sulfate a relatively thick alkali film forms at the cathode surface with the bulk catholyte at low pH. A thick alkaline film at high temperature tends to degrade the glucose diffusing through it toward the cathode surface. Moreover, such a film will be inherently more unstable due to the lack of buffering action in the catholyte. For example, the addition of acid to the catholyte as previously suggested greatly disturbs the film.

Another real and important advantage of my process accrues from the use of the phenomenon of electroendosmosis. By its proper use and control I can nullify the effects of ionic movement inherent in electrolytic processes. Furthermore, I can neutralize the diffusion normally set up as a result of concentration differences on the two sides of the diaphragm. It can be seen at once that not only is this an excellent expedient for controlling pH precisely but that it can also be used to eliminate completely the diffusion of glucose from cathode to anode compartment. Thus high concentrations of glucose can be used in the catholyte without loss of yield due to oxidation in the anode compartment.

A further advantage arising from the use of my process is that the anions of the buffer salts which I use are irreducible at the cathode surface under the conditions employed and hence have no tendency to upset reduction by causing a deposit upon the cathode. In the case of acid solution of sodium sulfate, however, the sulfate anion is quite susceptible to reduction. Any disturbance of the alkaline film at the cathode surface, such as occurs when acid is added to the catholyte for pH control, will result in hydrogen reacting with the sulfate ion in acid solution. There follows a sulfide deposit on the cathode surface which if allowed to grow enough will completely stop reduction. This has been experimentally demonstrated. Likewise, the use of mixing has been found impossible in a sulfate process since it is accompanied by complete disturbance of the alkaline film at the cathode surface and shortly thereafter by cessation of reduction. On the other hand, when using sodium acid carbonate as the original electrolyte in my process I successfully bubble gaseous CO_2 through the bulk catholyte to maintain acid conditions and do so with no disturbance whatsoever of the alkaline film which has been set up at the cathode surface. This is real evidence that the alkaline film set up by me in an acid buffered solution as a result of positive steps taken to do so is inherently a more stable film than that which forms spontaneously during the electrolysis in a non-buffering electrolytic solution of sulfuric acid and sodium sulfate.

I have carried out the process of my invention using buffered electrolytes with very good results while employing standard electrodes such as pure lead, amalgamated lead and amalgamated zinc as the cathode. None of these electrodes, however, was found to possess high mechanical strength over a period of continued use. My invention is also concerned, therefore, with novel, mechanically strong and highly durable cathodes and methods of preparing the cathode surfaces for successful use. I have found that nickel or

galvanized iron will serve excellently to produce a lasting surface, internally strong and highly efficient. The surfaces must be carefully prepared in order to produce the desired results. Using nickel as a cathode, I have achieved higher current efficiencies than any which, to my knowledge, have been reported in the electrolysis of acid solution of glucose. For example, one current efficiency at 95% reduction of glucose to sorbitol was 50%. The desired results are secured by first etching the surface of the metal electrode, for instance with acid, and then immersing the etched electrode in a bath of acid and a mercury salt until the metal acquires a shiny appearance. Thus I produce an electrode surface which will operate at high current efficiency and at the same time I have an electrode of real strength and durability. The advantages to be found in the use of strong, durable electrodes and in such a simple method of preparing an efficient surface are readily apparent. Further reference will be made, hereinafter, to the results obtained from the use of my improved electrodes. This subject matter, however, is claimed in my co-pending divisional application Ser. No. 225,269 filed May 8, 1951.

The characteristics of my invention will be best understood and appreciated from the following detailed description of a preferred procedure in carrying it out and as suggested in the accompanying description of the cell.

The cell used is of well known standard design and it will be understood that any desired or convenient arrangement of the elements of the cell may be made within the scope of the process defined. The cathode consists of a metal plate and the anode may consist of plates, rods, mesh, etc. The volume of catholyte may best be described as consisting of 13 liters per 200 square decimeters of cathode plate, while the anolyte is of approximately the same ratio to anode surface. The anode is separated from the cathode by a diaphragm of porous Alundum of about 0.5 cm. wall thickness and a permeability of about 5×10^{-5} D'Arcys. The catholyte is confined to the space between the cathode plate and the diaphragm and the anolyte surrounds the anode. The distance between cathode surface and anode surface may vary upward from about 1.5 inches but in order to achieve high current efficiencies should not be much above 3 inches.

In preparing to carry out the process of my invention a solution of glucose or other sugar and electrolyte is introduced into the cathode compartment and a solution of electrolyte into the anode compartment. The porous diaphragm will allow the passage of ions under the influence of the electric current but in general hinder the diffusion of sugar molecules from the catholyte into the anolyte. The diffusion of sugar may be stopped by setting up electroendosmosis of anolyte into the catholyte compartment. Makeup anolyte is then added to the anode compartment as needed.

The concentration of sugar and electrolyte may be varied widely, but it has been found that $\frac{1}{2}$ to 2 molar electrolyte salt in the catholyte and 200 to 325 grams per liter of sugar in the catholyte and an acid anolyte of 1 to 3 molar concentration gives satisfactory results. The ratio of metallic cation to anion, e.g. sodium to phosphate, is highest at the cathode surface, decreases sharply in the bulk catholyte, and is lowest in the anolyte where the cation is predominately hydrogen. The anion initially need not be the same in anolyte and catholyte and the metallic cation may be so-

dium potassium, or the like. Obviously a pH gradient exists from cathode surface to anode surface and it follows the curve exhibited by the metallic cation to anion ratio, being highest at the cathode surface, dropping sharply in the bulk catholyte and being very low in the acid anolyte. Required conditions, such as a certain pH, conductivity, etc. may be effected by varying the anolyte makeup.

The cathode consists of a metallic plate preferably treated in the manner already outlined, and the anode is preferably of lead or lead dioxide. The process of my invention can be carried out using pure lead or treated lead, zinc, nickel or galvanized iron as the material of the cathode. The passage of electric current through the cell liberates hydrogen at the cathode and this in turn combines chemically with glucose or other reducible sugar to produce the corresponding alcohol by a chemical reaction which is well known and needs no further explanation here. The variables of current density, pH of catholyte, concentration, temperature, etc. can be varied successfully within wide limits.

As already intimated, the process of my invention employs as electrolytes alkali metal salts of which the anions are irreducible at the cathode surface under the conditions of high hydrogen overvoltage existing there during electrolysis. In the first place, only cathode materials exhibiting high hydrogen overvoltage are useful in this process, and in the second place, only electrolytes which will resist reduction indefinitely at the cathode surface will leave the cathode uncontaminated and capable of operating at high efficiency. For example, it has been found that phosphate and carbonate ions are exceptionally advantageous in this respect. Sulphate salts are definitely inferior. In sulphate runs reduction of the sugar is likely to cease because of the formation of a contaminating sulfide film on the cathode surface resulting from reduction of sulphate ion. I have discovered that by various methods of introducing depolarization following the start of electrolysis, the reduction of sugar can be carried out at high current efficiency with the bulk catholyte in acid condition using a variety of cathode and electrolyte salts. It should be clear that in this disclosure a distinction is made between electrolysis which goes on whenever current is flowing through the cell producing hydrogen formed at the cathode, and the reduction which is the utilization of the hydrogen formed at the cathode surface by electrolysis. By depolarization is meant, herein, the setting up of an alkaline film at the cathode surface and the subsequent reduction of glucose by cathodic hydrogen; in other words, cathodic reduction following setting up of the alkaline film where sugar acts as the depolarizing agent. It is of course clear that any glucose which is to be reduced must diffuse through the alkaline film in order to react with the hydrogen being generated at the cathode surface. Since alkali degradation of sugar is fairly rapid at moderately elevated temperatures, the thickness of the alkaline film is of importance in its relation to product quality.

The setting up of the alkaline film is an important and necessary step in the depolarization required in carrying out the process of my invention. Several procedures are entirely satisfactory. One of the most effective is to add a small amount of sodium hydroxide solution to the catholyte directly at the cathode surface. When electrolysis but not reduction is going on and

sodium hydroxide is added in the manner suggested, there is a marked decrease in the rate of evolution of the hydrogen gas which is immediately observable to the eye. On testing the pH of the bulk catholyte it is found to be practically unchanged. For example, this technique may be used to initiate depolarization by using $\frac{1}{2}$ to 2 molar sodium dihydrogen phosphate as the electrolyte in the cathode compartment. This salt gives a distinctly acid pH in solution and the pH of the bulk catholyte remains unchanged by depolarization. The buffer action of this salt is of value in maintaining the pH of the bulk catholyte when using this procedure for depolarization.

Another very effective method of depolarization consists in mixing sodium dihydrogen phosphate with sodium hydroxide in the catholyte until the pH of the bulk catholyte is about 6.5 but always lower than 7.0. This produces a mixture of Na_2HPO_4 and Na_2HPO_4 in the cathodic solution. Phosphoric acid may be used in the anolyte. Electrolysis is started with high current density varying up to 2 amperes or more per square decimeter of cathode surface. Usually this high current density moves enough sodium to the cathode to start the reduction without any other provision for depolarization. At the same time electroendosmosis is set up, and by the time reduction is well under way the bulk catholyte is at a lower pH than the original. At this point current density may be decreased to slow up or stop electroendosmosis.

Still another effective method of depolarization is to make up 1 molar sodium bicarbonate solution in the catholyte. The pH of this solution is about 8. Upon commencing electrolysis the depolarization takes place spontaneously after which carbon dioxide is bubbled into the catholyte until there is a positive excess of CO_2 in the solution. This, of course, insures the acidity of the bulk catholyte and its pH drops to between 6 and 7. Carbon dioxide is bubbled into the catholyte in sufficient amount to insure saturation of the bulk catholyte as long as reduction continues. To avoid waste of CO_2 , however, phosphoric acid may be used in the anolyte, high current density impressed at the start, and the bulk catholyte acidified by the electroendosmosis of phosphoric acid into the catholyte. In this case the sodium bicarbonate acts merely as an aid to depolarization and the anion is replaced by the phosphate anion. In the same general manner sodium di-basic phosphate, Na_2HPO_4 , can be used.

Still a further procedure which may be used for depolarization when the cathode is not a mercury treated metal at the start of electrolysis, is to add a small amount of mercury salt to the anode compartment. In a cell which otherwise cannot be made to depolarize satisfactorily, the movement of the mercury ions to the cathode is followed by a marked decrease in hydrogen gas evolution and reduction of the sugar begins to take place. The addition of the mercury salt to the anolyte simply insures perfect distribution as the ions move to the cathode; obviously the salt can be added to the catholyte itself.

Although electroendosmosis is useful in this technique and is particularly effective, it will be understood that any method of acidifying the bulk catholyte as desired may be employed, such as the addition of acid to the catholyte in the region of the diaphragm or in the bulk, but never directly at the cathode surface.

Once depolarization is established and the reduction is under way, it is possible to run quite

high current density for a short time without upsetting the reducing conditions or the pH of the bulk catholyte. For example, it is possible to run up to 4 amperes per square decimeter and such current density variation allows the employment of electroendosmosis to control catholyte pH throughout the reduction process. The catholyte tends to become basic, the introduction of acid is necessary to neutralize, and this may be achieved readily by electroendosmosis of acid from the anolyte. By using sodium phosphates and sodium bicarbonate as anionic buffers, it has been found a temperature level of 40-50° in the bulk catholyte is permissible for several hours with the production of water white catholytes. Probably the explanation of this fact is that a thinner alkaline film is formed at the cathode surface with consequent lessening of the degradation of glucose diffusing through it to the cathode surface.

The following table is illustrative of typical runs of the process of my invention:

Table I

Run No.	Glucose conc.	Catholyte Make-up	Anolyte Make-up	Cathode	C. D.	T ° C.	Operating Hours	Catholyte pH	Per Cent S. R.	C. E. Per Cent	Catholyte Appearance
1	320	{1 M NaH ₂ PO ₄ , 3/4 M NaOH}	{2-3 M H ₃ PO ₄ , do}	Pb.....	0.70	40-45	22 1/2	4-5	76	43	water white.
2	320	{1 M NaH ₂ PO ₄ , 3/4 M NaOH}	do	Pb-Hg	0.70	40-45	42	5-6	99	52	Do.
3	320	{1 M NaH ₂ PO ₄ , 3/4 M NaOH}	do	do	0.70	40-45	42	5-6	99	55	Do.
4	325	{1 M NaH ₂ PO ₄ , 3/4 M NaOH}	do	Zn-Hg	0.50	40	24	4-5-6	92	66	Do.

Glucose concentration is in grams of glucose (anhydrous) per liter of solution.

Catholyte make-up is initial concentration of electrolyte per liter of solution in mols of electrolyte.

Anolyte make-up is the same.

Cathode refers to the metal (or treated metal) plate used.

C. D. is current density in amperes per square decimeter of cathode surface. This is given to represent approximately the average operating C. D. It was not absolutely fixed at the given figure for the entire run but was varied as need for varying it arose.

T deg. C. is temperature range of bulk catholyte for the majority of operating hours.

Catholyte pH is pH in the bulk following depolarization and adjustment by electroendosmosis or other means and represents fairly the range of variation during most of the operating time of the cell. A range of 2-7 pH was found perfectly operable.

Percent S. R. is percent sugar reduction as determined by Fehling's test using the Lane and Eynon method.

C. E. percent is current efficiency at the percent S. R. given as determined from the Fehling's tests.

The following is a description of my method of preparing the cathode surfaces. In the case of pure lead, the use of nitric acid of such strength as to etch the metal surface is sufficient. This is approximately 6 N, but a wide variation in concentration is permissible provided the etching is thorough. This is, of course, followed by a water wash. In the case of the Pb-Hg or Zn-Hg cathode, the cathode is first rinsed in the dilute nitric and then in water, following which the complete cathode is immersed in a dilute nitric acid-mercuric nitrate bath. The mercury is al-

lowed to plate out at room temperature until the cathode has a shiny appearance, after which the cathode is washed in water and is ready for use.

The advantages of such a simple method of mercury treating the cathode are obvious since no handling of liquid mercury is entailed and the amount of mercury plated out can be controlled exactly by regulating the time of immersion in the bath. The mercuric nitrate dissolves readily in fairly concentrated nitric acid and can then be diluted as desired. The bath can be used over and over provided the mercury used is replaced. The cathode material must at all times be handled with care and the surface protected from roughing, chemical action, etc.

I purposely call this cathode preparation a mercury treatment rather than an amalgamation because even a short treatment which does not leave the cathode with an amalgamated appearance will result in satisfactory reduction. I have pointed out previously that just traces of mercury will depolarize a pure metal cathode, lead

for example. The cathode of run No. 1 was pure lead however, depolarized with dilute sodium hydroxide solution. The ease and economy of such

40 a method of cathode preparation results in a considerable improvement over the traditional method of rubbing mercury into the lead or zinc surface by hand with consequent variations in the degree of amalgamation over various sections of the metal surface and severe weakening
45 of the metal.

Lead and zinc cathodes even when prepared by this mercury treatment embrittle with age and lose most of their mechanical strength in time. However, I have developed mechanically enduring cathodes which operate at high current efficiencies in buffered acid catholytes. As the cathode material I use a metal which is mechanically strong, which is substantially insoluble in mercury and highly resistant to its weakening effect but which is capable, either directly or indirectly of superficial surface amalgamation, the amalgamated surface being extremely thin but highly perfect in surface structure. This, of course, excludes the use of lead which is mechanically weak, copper which is weak and highly soluble in mercury, and zinc which is also highly soluble in mercury. One of the cathodes discovered by me is nickel, etched in concentrated nitric acid and then mercury treated. Iron can also be used but I prefer to first galvanize before mercury treating. The reason for this is that the over-voltage of iron is low and that of zinc is high and is well known that by the process of hot dipping a very thin and highly perfect zinc coat can be formed on the iron. I prefer to first form and etch the galvanized iron electrode and then redip it in molten zinc near the melting point, re-etch and then mercury treat. This produces a relatively thick zinc-mercury coating and coats

all exposed edges. Either electrode serves the purpose of producing lasting internal strength and high current efficiencies, but nickel is to be preferred in spite of its higher cost because of the ease of handling and the higher current efficiencies obtainable from its use.

8. The process defined in claim 1 further characterized by the step of depolarizing the cathode by applying sodium hydroxide to the cathode surface.

5 9. The process defined in claim 1 further characterized by the employment of electroendosmo-

In run No. 6 carbon dioxide was bubbled into the catholyte during reduction in order to maintain acidity there. There was at all times an excess of CO₂ in the sugar solution.

Having thus disclosed my invention and described in detail various illustrative ways of practicing it, I claim as new and desire to secure by Letters Patent:

1. A process of producing a polyhydric alcohol in an electrolytic cell having anode and cathode compartments separated by a permeable diaphragm, which comprises the steps of maintaining in the cathode compartment an acid solution at pH not less than 2.5 of the sugar corresponding to the said alcohol together with a buffer salt of a weak acid and an alkali metal, the anions of which are irreducible at the cathode under the conditions imposed, maintaining an acid anolyte of pH 0 to 7 in the anode compartment, flowing an electric current through the cell at a density of not over 4 amp./sq. dec., forming an alkaline film at the cathode, and causing the sugar to pass through the alkaline film to the cathode and to be reduced to alcohol by hydrogen liberated at the cathode.

2. The process defined in claim 1 further characterized by the employment of phosphate anion in the acid anolyte and in the acid catholyte.

3. The process defined in claim 1 further characterized by the employment of carbonate anion in the acid anolyte and in the acid catholyte.

4. The process defined in claim 1 further characterized by the employment of carbonate anion in the acid catholyte and phosphate anion in the acid anolyte.

5. The process defined in claim 1 further characterized by the employment of electroendosmosis to control pH in the bulk catholyte.

6. The process defined in claim 1 further characterized by the control of pH in the bulk catholyte by varying the intensity of electric current through the cell and the amount of electroendosmosis induced thereby.

7. The process defined in claim 1 further characterized by the step of applying liquid alkali to depolarize a cathode immersed in acid catholyte.

sis to establish depolarization of the cathode surface.

20 10. The process defined in claim 1 further characterized by the step of depolarizing the cathode by adding sodium bicarbonate to the catholyte.

25 11. The process defined in claim 1 further characterized by the steps of adding gaseous CO₂ to the catholyte, saturating the same therewith and maintaining it in acid condition therewith, while using carbonate anion therein.

12. A process of producing sorbitol in an electrolytic cell having anode and cathode compartments separated by a permeable diaphragm, which comprises the steps of maintaining in the cathode compartment an acid solution of glucose and a buffer salt of a weak acid and an alkali metal at a pH not less than 2.5, the anions of which are irreducible at the cathode under the conditions imposed, maintaining an acid anolyte of pH 0 to 7 in the anode compartment, flowing an electric current through the cell at a current density of not more than 4 amps./sq. dec.

35 40 forming an alkaline film at the cathode, and causing the glucose to pass through the alkaline film to the cathode and to be reduced to sorbitol by hydrogen liberated at the cathode.
